Patented May 30, 1922.

UNITED STATES PATENT OFFICE.

LERoy BAUMGARTL, OF CHICAGO, ILLINOIS, ASSIGNOR TO FEDERAL CEMENT TILE COMPANY, OF CHICAGO, ILLINOIS, A CORPORATION OF ILLINOIS.

ROOF STRUCTURE.

1,417,487.

Specification of Letters Patent. Patented May 30, 1922.

Application filed March 21, 1921. Serial No. 454,113.

To all whom it may concern:

Be it known that I, LEROY BAUMGARTL, a citizen of the United States, residing at Chicago, in the county of Cook and State 5 of Illinois, have invented a new and useful Improvement in Roof Structures, of which the following is a specification.

My invention relates more particularly to roof structures formed of slabs of cement 10 or the like material, ordinarily assembled to form the roof, in overlapped courses or rows, the slabs of adjacent rows being arranged in staggered relation; and more especially to structures wherein the joints between 15 edge-to-edge disposed slabs are formed by applying any suitable filling material to the channels provided in the upper surface of the roof structure at the joints between adjacent slabs; my primary object being to 20 provide improvements in structures of the character just referred to, to the end that the joints produced may be rendered more perfect.

Referring to the accompanying drawings: 25 Figure 1 is a plan view of a portion of a roof structure constructed in accordance with my invention, the joint-forming cement at certain of the joints thereof being broken away. Figure 2 is a perspective view of one 30 of the similar slabs. Figure 3 is a broken section taken at the line 3 on Fig. 1 and viewed in the direction of the arrow. Figure 4 is a section taken at the line 4 on Fig. 1 and viewed in the direction of the arrow. 35 Figure 5 is a view like Fig. 3 of a slight modification of the disposition of the joint-forming filling material; and Figure 6, a view of the structure shown in Fig. 5 showing the filling material as covered with a 40 skin of such character as to form a sheathing for the underlying body of joint-forming material.

In accordance with the illustrated, preferred, embodiment of my invention, the slab 45 is provided of the form shown in the drawings, Fig. 2 showing one of the similar slabs in perspective. The slabs, represented at 7, are provided of rectangular form and are preferably of the thin type with reinforcement (not shown) disposed in the tensile zone of the slabs. The slabs are provided

along their upper surface adjacent each of opposite edges thereof, with series of upwardly-extending ribs which extend preferably the full length of the slabs. Each 55 series of ribs referred to is shown as comprising two ribs 8 and 9, affording therebetween the channels 10 extending the full length of the slabs, the ribs 8 being set back from the adjacent edges of the slabs, as 60 shown, to present the lengthwise-extending recesses 11 in the upper surface of the slab at opposite edges thereof. The slab is thickened in a direction lengthwise thereof and along its medial line to form a roll 12 65 which extends from one end of the slab to a point short of the opposite end thereof, the under side of the slab at the end of the latter to which the roll 12 extends, being recessed as represented at 13. 70

In the assembling of the slabs to form a roof structure, they are arranged in edge-to-edge relation as shown in Figs. 1, 3 and 4, to form a plurality of courses, with the upper edges of the slabs of each course, except the 75 uppermost one, overlapped by the lower edges of the courses immediately above them, the slabs of adjacent courses being arranged in staggered relation to cause the joints between the slabs arranged side by side, to extend into the recesses 13 of the slabs of the course next above them, as shown. In the arranging of the slabs in edge to edge relation, as stated and shown, the opposing recesses 11 afford at each joint, a groove 14 80 extending lengthwise of the slabs, the adjacent, opposed edges of the slabs being preferably spaced a slight distance apart as shown of Figs. 1, 3 and 4. In accordance with the showing in Figs. 1, 3 and 4, any suitable 85 plastic cementitious material, such as that commonly employed to fill the joints between roof slabs, is applied to the upper surfaces of the slabs to extend, preferably, the full length thereof at the joints, the applied material referred to, and represented at 15, being provided of such thickness as to extend into the channels 14, into the channels 10, across the tops of the ribs 8 and 9, and at least part way down into the spaces between adjacent slabs, the body of material 15 being so disposed that it will present a 90 95 100

cross-sectional shape as shown in Fig. 3. Before applying the upper courses of slabs, ribbons 16 of the cementitious material referred to are applied across the upper surfaces of the slabs adjacent their upper edges to extend at right angles to the length of the slabs and in such position that the lower edges of the slabs next above them will bear down against these ribbons of cementitious material. The masses 15 of cement, especially at the upper ends of the joints over which they extend, are of sufficient volume that when the slabs next above them are applied to position thereon, in staggering relation thereto, the walls of the shallow recesses 13 will cause these masses, where engaged by the row of slabs next above them, to be mashed or squeezed down substantially to the cross-sectional shape shown in Fig. 4, thereby causing the cementitious material to completely fill the spaces presented between the slabs at their recessed portions 13 and the ribbed portions of the slabs immediately beneath them.

In the structure shown in Fig. 5, which illustrates a modification of the invention, the mass of material 15 is shown as built up slightly higher at the joint between the slabs and extends flush with the outer edge represented at 17, of the ribs 9.

In the structure shown in Fig. 6 the body 15 of cementitious material is disposed as shown in Fig. 5, but instead of being exposed to the weather, is covered by a sheathing, represented at 18, of any suitable material which tends to protect the mass 15 against the deleterious action of the elements.

It will be noted that in all of the structures shown a body of the joint-forming material, of relatively large cross-section is provided at the joint between the slabs arranged in edge to edge relation, and at both sides of the body so formed, fairly thick bodies of the material are afforded by reason of the provision of the channels 10 into which the material extends and thus there is little, if any, danger of the material forming the joint drawing away from contact with the slabs, as for example in the drying out of the filling material, and even if the edge portions of the body of filling material draw away from the slabs sufficiently to permit water to enter between it and the slabs, the water could not pass beyond the channels 10, and thus the joints would be maintained water-tight.

It will also be noted that the ribs 9 serve to dam the water running down the slabs and to a great degree divert it from the joints between the slabs.

In using the expression "slabs" in the foregoing description and the following claims, I wish to be understood as intending it to express any form of body, such as,

for example, so-called flat slabs, or tile, of such character that a roof structure may be formed therefrom.

While I have illustrated a particular construction embodying my invention, I do not wish to be understood as intending to limit it thereto, as the same may be variously modified and altered without departing from the spirit of my invention.

What I claim as new, and desire to secure by Letters Patent, is:

1. In combination, slabs arranged side by side in edgewise opposed relation, said slabs presenting an upwardly opening groove at their opposed edges for receiving material to fill the joint between the slabs, the upper surface of each slab having an upwardly extending rib extending lengthwise thereof and located between said grooves and the main body portion of the slab, the upper surfaces of said slabs also containing channels extending alongside said ribs, and plastic, cementitious, filling material extending into said groove and into said channels and forming an exposed filler rendering water-tight the joint between said slabs.

2. In combination, slabs arranged side by side in edgewise opposed relation, each of said slabs having the upper portion of an edge thereof set back from the lower portion thereof to form an upwardly opening groove at the opposite edges of the slabs, each of said slabs presenting an upwardly extending rib extending lengthwise thereof and located between said set-back portion of the slab, each of said slabs containing a channel in its upper surface extending alongside said rib, and plastic, cementitious, filling material filling said groove and extending into said channels and forming an exposed filler rendering water-tight the joint between said slabs.

3. In combination, slabs arranged side by side in edgewise opposed relation, each of said slabs having the upper portion of an edge thereof set back from the lower portion thereof to form an upwardly opening groove at the opposite edges of the slabs, each of said slabs presenting an upwardly extending rib extending lengthwise thereof and located between said set-back portion of the slab, and a second rib spaced from said first-referred-to rib and forming therewith a channel in the upper surface of the slab, and plastic, cementitious, filling material filling the said groove and extending into said channels and forming an exposed filler rendering water-tight the joint between said slabs.

4. In combination, slabs arranged side by side in edgewise opposed relation, said slabs presenting a groove at their opposed edges and channels in their upper surfaces located at opposite sides of said grooves and adjacent thereto, respectively, plastic filling

material filling said groove and channels and extending above the upper surface of the slab, and forming an exposed filler rendering water-tight the joint between said 5 slabs, and a third slab, overlapping said first-referred-to slabs, and containing in its under side at one end, a relatively shallow

recess at which it overlaps one end of the said groove and channels and in the assembling of said slabs, squeezes the filling into 10 close engagement with the under side of said recess.

LEROY BAUMGARTL.
